UNITED STATES PATENT OFFICE.

JUDSON G. COFMAN, OF PRAIRIE, WASHINGTON.

DESIGN FOR A BRUSH-HOOK.

SPECIFICATION forming part of Design No. 20,684, dated April 21, 1891.

Application filed March 10, 1891. Serial No. 384,497. Term of patent 14 years.

To all whom it may concern:

Be it known that I, JUDSON G. COFMAN, a citizen of the United States, residing at Prairie, in the county of Skagit and State of Washington, have invented and produced a new and original Design for a Brush-Hook, of which the following is a specification, reference being had to the accompanying drawing, in which the figure represents in perspective a brush-hook embodying my invention.

The design consists in the configuration of the blade.

The letter a indicates the eye of the blade, a' the line of the cutting-edge, and $a^2 a^3$ the lines of the back edge of the blade. The blade forward of the eye tapers longitudinally and transversely to the extreme outer point

a^3 , and the longitudinal lines range diagonally to the eye a . The exterior surface of the blade at the eye is rounded transversely, as at a^4 . The line a' of the cutting-edge extends in a straight direction from its heel to the extreme point a^3 , and the lines $a^2 a^3$ of the back edge incline slightly toward the line a' of the opposite or cutting edge and are curved inwardly, as at a^5 , to a meeting with the line a' at the point a^3 .

I claim—

The design for a brush-hook herein shown and described.

JUDSON G. COFMAN.
